SNOW PLOW

Cassius I. Southwick, Grand Rapids, Mich.

Application August 3, 1936, Serial No. 93,927

7 Claims. (Cl. 37—42)

This invention relates generally to snow plows and more particularly to an attachment for the diagonal blade type of snow plow.

The ordinary diagonal blade type of snow plow merely shifts the snow to the side of the road and packs it thus forming a snow bank immediately adjacent the trailing edge of the snow plow and this is objectionable inasmuch as a wall of snow soon builds up which prevents expeditious removal of additional snow.

My invention contemplates an attachment or construction which will not only shift the snow from the roadway but which will also throw the snow well aside from the roadway. Furthermore, my construction is so devised as to cause the snow to be thrown upwardly as well as outwardly, whereby plenty of space will be available for its disposal.

Another advantage of my invention resides in its simplicity and sturdiness. It will be noted that there are no rotating or moving parts in my construction, the aforesaid desirable results being obtained by the novel positioning of the several rigid members. This fact, of course, makes for economy both in construction and maintenance. It is to be understood that my invention can be initially built in a construction or else can be constructed as a unit which is to be permanently attached to a diagonal blade type of plow.

Another advantage of my novel snow plow is that it may be utilized as a follow-up plow for other snow plows of the ordinary diagonal blade type to widen the roadway which has been partially cleared by them. When this is done, the vertical plate of my snow plow, adjacent its trailing edge, cuts into the more or less packed bank of snow along the roadway and shears off a portion thereof throwing it outwardly and upwardly and thus preventing it from falling back into the roadway.

Yet another advantage of my invention resides in the pointed cutting construction at the forward edge of the vertical plate near the trailing end of the scraper blade, this point engaging and loosening ice and snow whereby its removal is assured.

Other objects and advantages of the present invention will appear from the following description, taken in connection with the accompanying drawings, in which,

Fig. 1 is a front view of a snow plow made in accordance with this invention mounted on a truck. The colter is in position to cut away the bank formed at the side edge of the road.

Fig. 2 is a plan view of the plow and of a portion of the front end of the truck.

Fig. 3 is a side elevation of the plow and truck as illustrated in Fig. 2.

Fig. 4 is a horizontal section taken on line 4—4 of Fig. 1.

Like reference numerals refer to like parts throughout the several figures of the drawings.

As clearly shown in Fig. 2 of the drawings, the scraper blade 1 is attached onto the truck T by means of members including the rearward extensions 2 and 3. These extensions form part of the mounting construction. A cutting plate or colter 4 is positioned near the trailing edge of the scraper blade 1. This member 4 is rigidly attached onto the scraper blade 1, by means of the angle clips 5, see Figs. 3 and 4, whereby it extends in substantial parallelism to the path of movement of the truck.

The lower end of the colter has an angle member 6 extending laterally therefrom. See Figs. 1 and 4. This flange 6 is curved upwardly at its rear edge as indicated at 7. See Fig. 3. Its forward edge is pointed as clearly shown in Fig. 4. The main body portion of the colter 4 extends slantly upwardly at its front edge, see Fig. 3, and thus a point 8 is formed at the leading edge of the colter. This is clearly shown in Fig. 4 of the drawings.

A curved plate member or fillet 9 is flanged at one of its substantially vertical edges as indicated at 10 and rivets 11 pass through this flange and through the colter 4, see Figs. 3 and 4, to maintain the member 9 in position. At its opposite substantially vertical edge, fastening bolts 12 are provided. Thus the member 9 is securely held in position. This member extends between the scraper blade 1 and the colter 4 and slants upwardly to provide a path for the snow thrust thereagainst by the diagonally positioned scraper blade 1. Also, ice and packed snow, which are loosened by the point 8, will slide upwardly along the surface of this fillet plate 9.

The upper edge of the plate 9 has a curved extension 13, this extension extending outwardly over the top of the colter 4 as clearly shown in Fig. 1. Thus a path is formed for the outwardly thrust material.

A mold board 14 is bolted at the top of the scraper blade 1 and receives a brace 17 fastened at 18 thereto whereby it is held in position. The other end of the brace 17 is connected onto the mounting structure between the truck and the snow plow.

The operation

During operation the forward movement of the scraper blade 1 causes the snow to be moved upwardly and laterally toward the colter 4 and the fillet plate 9. Also, the point 8 loosens any material in its path and causes the same to travel upwardly along the surface of the fillet plate 9.

The material flows laterally, as stated, and then travels upwardly over the extension 13 due to its velocity, and is then thrown outwardly as indicated in Fig. 1 of the drawings.

Furthermore, the leading and slanting edge of the colter plate 4, see Fig. 3, engages against any bank of snow which may be in its path for any reason and shears off the projecting portions thereof. The snow and ice travel rearwardly and upwardly from adjacent the point 8 and are carried outwardly by the impact of the main body 20 of the snow which is being thrown outwardly and upwardly. Also, the slight outward slant of the colter 4 and fillet 9 aid in this outward movement.

From the above description it will be appreciated that my novel snow plow not only moves the snow to the side of the roadway but it also throws the removed snow upwardly and outwardly so that it will not be in the way of snow which is to be removed in subsequent operations of the snow plow.

My device, although seemingly simple in construction, is nevertheless highly efficient and accomplishes results which have been sought previously but which have not been accomplished by a structure of this character.

Therefore, having thus described my invention I claim as new the structure defined in the appended claims and this structure is to be considered comprehensive of all forms of structure coming within their scope.

I claim:

1. In a snow plow construction of the diagonal type having a scraper blade curved upwardly and rearwardly, an approximately vertical colter plate attached near the trailing edge thereof in substantial parallelism to the path of movement of the scraper blade, said colter plate having its front edge extending upwardly and rearwardly and a flange located near the bottom edge of the colter plate and extending inwardly under the scraper blade, said forward portion of the flange being pointed outwardly for the purpose described.

2. In combination, a scraper blade adapted to be mounted diagonally to the roadway over which it is to be pushed, a colter plate of flat construction, means for fastening the colter plate in parallelism to the path of travel of the scraper near one end of the blade, a fillet positioned between the blade and colter plate and having a lateral extension protruding over the upper edge of the colter plate for the purpose described.

3. A combination of elements as set forth in claim 2 but also having a moldboard fastened to the scraper blade, said moldboard curving forwardly and outwardly over the said lateral extension.

4. A snow plow of the character described comprising a diagonally positioned scraper blade, said scraper blade being mounted on an angle relative to a vertical plane, the upper edge of said blade being rearward of the lower edge, a colter, positioned in a plane parallel to the path of travel of the plow during the scraping operation, attached to and contacting substantially the entire trailing edge of the scraping blade, the forward edge of said colter extending slightly forwardly of the forward edge of the scraping blade, said extension on the colter being pointed for the purpose described.

5. A snow plow as described in claim 4 having a fillet of curved horizontal cross section which is attached to said colter and to said scraper blade and which spans the angular gap therebetween for the purpose described.

6. A snow plow as described in claim 4 being further characterized in providing an extension for said scraper blade, said scraper blade extension being attached to the upper trailing edge of said scraper blade, said blade extension extending upwardly and outwardly relative to the trailing end of said scraper blade.

7. A snow plow as described in claim 4 having an extension for said scraper blade, said scraper blade extension being attached to the upper trailing edge of said scraper blade, said blade extension extending outwardly and upwardly relative to the trailing end of the said scraper blade, said scraper blade extension extending to an approximately vertical position and having a forwardly curved portion at its upper extremity for the purpose described.

CASSIUS I. SOUTHWICK.
